ATTORNEYS

UNITED STATES PATENT OFFICE.

FRANK LEONARD TREES, OF JUNIATA, PENNSYLVANIA.

GREASE-CUP.

1,003,305.

Specification of Letters Patent. Patented Sept. 12, 1911.

Application filed April 21, 1911. Serial No. 622,441.

To all whom it may concern:

Be it known that I, FRANK L. TREES, a citizen of the United States, and a resident of Juniata, in the county of Blair and State 5 of Pennsylvania, have made certain new and useful Improvements in Grease-Cups, of which the following is a specification.

My invention relates to improvements in lubricating devices, and it consists in the 10 combinations, constructions and arrangements herein described and claimed.

An object of my invention is to provide a cup for holding hard grease of a semi-fluid nature with means for forcing the grease 15 through a feed opening.

A further object of my invention is to provide a device which may be readily filled and in which the cover forms a guide member for the stem of a movable plunger or 20 piston.

A further object of my invention is to provide a grease cup having a maximum capacity, owing to the fact that part of the mechanism for exerting a pressure on the 25 grease is disposed on the exterior of the cup rather than on the interior.

Other objects and advantages will appear in the following specification, and the novel features of the device will be particularly 30 pointed out in the appended claims.

My invention is illustrated in the accompanying drawings in which—

Figure 1 is a perspective view of the device in its operative position, and Fig. 2 is 35 a vertical section through the device.

In carrying out my invention I provide a cylindrical cup 1 of brass or other suitable material, having an integral bottom 2 preferably of a hexagonal shape for the purpose of 40 accommodating a wrench or other tool. The

bottom 2 has an integral extension 3 which is threaded at 4 and which may be screwed into an opening in a bearing (not shown).

A small feed passage 5 is provided which 45 communicates with the interior of the cup 1. The top of the cup is threaded as shown at 6, to receive a threaded ring 7 which is provided with an extension 8 on one side thereof. Surmounting the cup 1 is a cover 9 50 having a central opening 10. The cover has an arm 9^a which is pivoted to the extension 8 at 9^b. A spiral spring 11 surrounds the outer portion of the cup 1, the upper end of the spring bearing against the ring 7 and 55 the lower portion bearing against a collar 12 which is provided with upturned flanges 13.

A bail 14 is pivotally mounted on the flanges 13.

Within the cup 1 is a plunger 15 whose stem 16 is adapted to pass through the opening pin. The upper part of the stem 16 is provided with a notch 17 adapted to receive the bail. A stop-pin 18 is carried by the stem a short distance below the top. About midway between the plunger 15 and the 65 upper end of the stem is a notch 19 also adapted to receive the bail.

From the foregoing description of the various parts of the device, the operation thereof may be readily understood.

In filling the device the bail is pulled 70 upwardly and swung free from the stem. The plunger is then raised until it is within the cover, when the latter may be swung free of the cup into the position indicated 75 by dotted lines in Fig. 2. The cup is then filled with the grease and the cover is again swung into position. The bail is lifted against the tension of the spring and may be hooked in the notch 19. The tension of the 80 spring forces the plunger downwardly so that the grease is forced out of the opening into contact with the moving part which it is designed to lubricate. Where the cup is used with an automobile it may be left until 85 the bail has nearly reached the cover, when it may be lifted and slipped into the notch 17, as shown in Figs. 1 and 2.

Obviously the spring might be arranged 90 so that the bail could be lifted immediately over the end of the stem 16, thereby dispensing with the use of the notch 19, but in practice I prefer to provide the notch thereby obviating the necessity of a very stiff 95 spring.

I claim:—

1. A grease cup having a feed opening in its bottom, and provided with a threaded upper end, a threaded ring arranged to engage the threads of the upper end of the 100 cup, and provided with an extension, a cover having a central opening and being provided with an arm having a pivotal connection with the extension of the ring, a plunger disposed within said cup and provided with a stem arranged to extend through the central opening in the cover, a collar slidably disposed on the exterior of said cup, a spiral spring disposed between said collar and said ring, and a bail pivotally 105 mounted on said slideable collar and adapted to engage the stem.

2. A grease cup having a feed opening in its bottom, a cover hinged to said cup, and provided with an opening, a plunger having a stem arranged to extend through said opening, a collar slidably disposed on the exterior of said cup, a spiral spring surrounding said cup, and bearing at one end upon said collar, and a bail pivotally mounted on said collar and adapted to engage the stem.

3. A grease cup having a feed opening in its bottom, a cover hinged to said cup and provided with an opening, a plunger having a stem arranged to extend through said opening, a guide member slidably disposed on the exterior of said cup, a spring, bearing at one end upon said guide member, the

other end of the spring bearing against a portion of the cup, and means for detachably securing said guide member to said 20 stem.

4. A grease cup having a feed opening at its bottom, a cover hinged to said cup and provided with an opening, a plunger having a stem arranged to extend through said opening, a collar slidably disposed on the exterior of said cup, a spring for holding said collar normally away from said cover, and means for detachably securing said collar to said stem.

FRANK LEONARD TREESE.
